CLAIM

The ornamental design for a tabletop clamp, as shown and described.

DESCRIPTION

FIG. 1 is a front perspective view of a tabletop clamp, showing my new design;

FIG. 2 is a rear perspective view thereof;

FIG. 3 is a right side elevation view thereof;

FIG. 4 is a left side elevation view thereof;

FIG. 5 is a rear elevation view thereof;

FIG. 6 is a front elevation view thereof;

FIG. 7 is a top plan view thereof;

FIG. 8 is a bottom view thereof; and,

FIG. 9 is a perspective view thereof, also showing the tabletop clamp in use over a tabletop, which is shown in phantom lines.

The tabletop and slots in the handle shown in phantom lines depict use and environment, and form no part of the claimed design.
